UNITED STATES PATENT OFFICE

WILLIAM H. ROSE, OF JERSEY CITY, NEW JERSEY

CONTAINER CLOSURE

Application filed May 8, 1930. Serial No. 450,865.

My invention relates to container closures and refers particularly to closures adapted for use with readily penetratable containers.

The object of my invention is a container closure, preferably of metal, capable of adaptation as a closing means for containers composed of penetratable material, such as paper, cardboard, fibrous materials and similar substances.

10 A closure of this character should be economic in production, readily applied, capable of removal and replacement without injuring the container walls, and capable of producing an air-tight and liquid tight seal between the closure and the container.

The container closure of my invention which possesses all of the above-mentioned, and other, valuable features comprises an anchor, or anchoring member capable of attachment to the outer wall of a container without causing leaking at the points of attachment, and a closure member capable of placement over the open end of the container and capable of attachment to the anchor, thus forming a seal between the closure member and the wall of the container.

My device also possesses the great practical value that it can be readily removed to gain access to the contents of the container and re-placed in sealed position without injury to the container.

30 The many advantages of my device will be evident upon a consideration of my specification and drawings explaining several modifications of my device, but I do not limit myself to the particular modified forms thus explained and shown.

In the accompanying drawings illustrating modified forms of the device of my invention similar parts are designated by similar numerals.

Figure 1 is a side view, partly in section illustrating one form of the device of my invention attached to a container.

45 Figure 2 is a fragmentary vertical section of a modified form of the device of my invention.

50 Figure 3 is a fragmentary vertical section of a modified form of the device of my invention.

Figure 4 is a fragmentary vertical section of a modified form of the device of my invention.

Figure 5 is a fragmentary vertical section of a modified form of the device of my invention.

Figure 6 is a fragmentary vertical section of a modified form of the device of my invention.

Figure 7 is a fragmentary vertical section of a modified form of the device of my invention.

Figure 8 is a perspective view of one form of an anchor of the device of my invention.

Figure 9 is a fragmentary plan view showing one form of end attachment of one form of anchor.

Figure 10 is a fragmentary plan view showing a modified form of end attachment of one form of anchor.

Figure 11 is a perspective view of the anchor shown in Figures 4 and 6.

Figure 12 is a perspective view of the anchor shown in Figure 8, with the rib extending across the top thereof.

The particular form of my device shown in Figures 1 and 8 of the accompanying drawings comprises an annular anchoring member having the central continuous rib 20, and a plurality of right angled positioned 80 prongs 21, 21, said prongs being inserted into the side 22 of an annular container. The closure member consists of the central cover 23, which is extended into the channel-shaped flange 24 and a plurality of downwardly extended prongs 25, 25, the extremity of each prong extending downwardly beyond the anchor member and capable of being bent thereunder.

In operation, the anchoring member is 90 placed around the exterior face of the container, the teeth 21, 21, being inserted into the side 22 of the container. A soft, or resilient, washer 26 is placed upon the upper face of the wall 22, the closure member placed 95 upon the container with the wall 22 positioned within the channel-shaped flange 24. The cover is then pressed downwardly and the prongs 25, 25, bent inwardly beneath the anchoring member, thus causing the cover to 100

be maintained firmly in place and causing a hermetical closure of the container.

The modification shown in Figure 2 is similar to that of Figure 1, except that the rib 20 of the anchoring member is inclined with respect to the bent portions of the anchor prongs 21, 21 and hence is in a plane at angles to that of the container wall 22. In the closure of this modification the free end 10 of each prong 25 has an inwardly bent fastening member 27. In operation, the anchor is positioned as shown and the closure member is forced downwardly, each fastening member being bent slightly outwardly by the anchoring member, the resilience of the prong causing the fastening member to move beneath the anchoring member to maintain the closure in position.

In the modified form shown in Figure 3, the series of prongs 28 is positioned at an acute angle to the rib 20, while the series of prongs 29 is positioned at right angles thereto. The closure comprises the cover 30 having the channel-shaped flange 31, which is 25 extended outwardly 32, and downwardly 33 and has a plurality of prongs 34 capable of being bent under the anchor.

In the modified form shown in Figure 4, the anchor comprises the rib 35 and a plurality of prongs 36 which are bent inwardly 37, outwardly 38 and inwardly 39. The closure comprises the cover 40 having the channel-shaped flange 41 which is extended outwardly 42, then downwardly 43, and carries 25 a plurality of prongs the end 44 of each being capable of being bent beneath the anchor.

In the modified form shown in Figure 5, the anchor comprises the rib 45, having a series of prongs 46 bent angularly as 47 and 40 then inwardly as 48, and a second series of prongs 49 bent inwardly at right angles as 50, then outwardly as 51 and then inwardly as 52. The closure comprises the cover 53 having the channel-shaped flange 54, the lower 45 peripheral portion of which is turned inwardly to form the member 55 capable of placement beneath the anchor.

In the modification shown in Figure 6 the anchor is similar to that shown in Figure 4 except that the lower series of prongs is positioned angularly to those of the upper series, and the closure is similar to that shown in Figure 1.

In order to give increased stability to that 65 portion of the anchor extending beyond the container wall 22, if desired, a strip of paper, felt or other suitable material may be placed within the anchor. This strip may be applied to any of the forms of anchors shown, 80 or suitable for my purpose, and in Figure 7, I show this strip 56 adapted to an anchor comprising a rib 57, having two series of prongs 58 each being bent outwardly as 59 and inwardly as 60.

65 The two ends of the anchor may be fastened

together after placement around the container wall 22, spotwelding 61, 61 as shown in Figure 9, or a projecting tongue 62 of one end may be inserted through an opening 63 of the other end, as shown in Figure 10 and 70 then bent over.

In all of the modifications shown with the exception of that of Figures 2 and 5, the closure is attached to the anchor by bending its prongs beneath the anchor, while in the 75 modification of Figures 2 and 5, the closure is pressed downwardly the prong 27 of Figure 2 and the prong 55 of Figure 5 springing into place beneath the anchor.

The anchor need not be a continuous one 80 extending around the wall of the container, as similar results can be obtained by a plurality of separate anchors properly positioned to receive the prongs of the closure.

In order to obtain access to the interior of 85 the container, the closure prongs are bent outwardly from contact with the anchor and the closure removed without injuring the container. The closure can thus be readily 90 replaced into closed position.

It will thus be seen that in the device of my invention an anchor having extended prongs is attached to the walls of a container by inserting said prongs within said wall allowing a portion of said anchor to extend 95 beyond said wall, and that the closure is attached to said anchor by means of prongs, or extended members carried by said closure and positioned beneath said anchor.

It will be further noted that the closure 100 may be readily removed without injury to the walls of the container and can be replaced and fastened into closed position.

I do not limit myself to the particular size, shape, number or arrangement of parts as 105 shown and described as these are given simply as a means for clearly describing the device of my invention.

What I claim is:—

1. In a container closure, in combination, 110 a container, an anchor spaced exteriorly from the outer face of a wall of said container, a plurality of prongs carried by opposite sides of said anchor and inserted within said container wall, a separate closure covering the 115 open end of said container and extending externally of the outer face of said anchor and a flange carried by said closure abutting upon the lower face of said anchor.

2. In a container closure, in combination, 120 a container, an anchor spaced exteriorly from the outer face of a wall of said container, a plurality of prongs carried by opposite sides of said anchor and inserted within said container wall, a separate closure covering the 125 open end of said container, a dependent flange carried by said closure externally of the outer face of said anchor and a plurality of prongs carried by said flange abutting upon the 130 lower face of said anchor.

container wall being positioned within said channel.

14. In a container closure, in combination, a container, a continuous anchor spaced exteriorly from the outer face of a wall of said container and extending around said container, a plurality of prongs carried by said anchor and inserted within said container wall; a separate channel-shaped closure covering the open end of said container and a dependent flange carried by said closure externally of the outer face of said anchor and a plurality of prongs carried by said flange abutting upon the lower face of said anchor said container wall being positioned within said channel.

Signed at New York City, in the county of New York and State of New York, this 5th day of May, 1930.
